Primary Examiner — R. Johnson(74) *Attorney, Agent, or Firm* — Sughrue Mion, PLLC(57) **CLAIM**

The ornamental design for an electronic keyboard, as shown and described.

DESCRIPTION

FIG. 1 is a top perspective view of an electronic keyboard showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines shown represent portions of the electronic keyboard and form no part of the claimed design.
